UNITED STATES PATENT OFFICE.

LEON BONDUEL, OF PARIS, FRANCE.

COMBINED WARDROBE, WASH-STAND, AND BATH-TUB.

SPECIFICATION forming part of Letters Patent No. 268,450, dated December 5, 1882.

Application filed July 27, 1881. (No model.) Patented in France May 5, 1880, No. 136,523.

To all whom it may concern:

Be it known that I, LEON BONDUEL, of Paris, Department of Seine, and Republic of France, have invented certain new and useful Improvements in Combined Wardrobe, Wash-Stand, and Bath-Tub; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention relates to improvements in cabinets containing a number of pieces of furniture for different purposes; and the object of my invention is to combine in such a cabinet clothes-press, night-table, wash-stand, and bath. I attain this object by the mechanism illustrated in the accompanying drawings, in which—

Figure 1 is a front elevation of the entire cabinet; Fig. 2, a front view of the door after removing the front plate; Fig. 3, a side elevation of the door, and Fig. 4 a view of the interior of the cabinet after removing the door.

Similar letters refer to similar parts throughout the several views.

On the back of the door Q is suspended the bathing-tub E by means of the hinged supports H and the chain O, running over the rollers N N' to the windlass R. The inside of the washing-tub is filled by the clothes-press A, closed by two small doors in the main door Q, and the wash-stand B. The doors of A are hinged vertically, while the wash-stand B may be turned horizontally, like the desk of a scrutoire. The wash-stand B contains a wash-basin, F, covered by a round looking-glass, P, and a reser-

voir, J, wherein the basin stands, and which 40 is emptied through a pipe to the reservoir S, when the wash-stand is returned to its vertical position. In the same manner is constructed the sitz-bath basin D, which, by the pipe I, is connected with the reservoir T. Two drawers, 45 C and C', are arranged on both sides of the sitz-bath basin D.

When the main door Q is entirely opened the interior of the cabinet shows a complete douching apparatus, composed of the foot-basin 50 4, the upper reservoir, M, filled by the hand-pump 1 through the piping U, the douche V on the top of the cabinet, and the douche 5 on the bottom. The seat 3 is hinged to the back wall of the cabinet. The cocks X, Y, and Z 55 serve to regulate the flow of the water in any direction desired, and through the cock 2 the upper reservoir can be emptied. The pipings I and I' supply from the upper reservoir water to the wash-basin F and the sitz-bath basin D. 60

Having thus fully described my invention, what I claim, and desire to secure by Letters Patent, is—

1. In a cabinet, the combination of the hinged seat 3 with the douches V and 5, substantially 65 as set forth.

2. In a cabinet, the combination of the upper reservoir, M, the foot-reservoir 4, and the piping U with the hand-pump 1 and the discharge-cock 2, substantially as and for the purpose 70 specified.

In testimony that I claim the foregoing I have hereunto set my hand this 14th day of August, 1880.

LEON BONDUEL.
